UNITED STATES PATENT OFFICE.

JAMES F. PIERCE, OF GLYNRICH, DELAWARE, ASSIGNOR TO AMERICAN VULCANIZED FIBRE CO., OF WILMINGTON, DELAWARE, A CORPORATION OF DELAWARE.

MANDREL FOR USE WITH APPARATUS FOR FORMING TUBES.

1,322,944.

Specification of Letters Patent.

Patented Nov. 25, 1919.

Application filed March 30, 1917. Serial No. 158,768.

To all whom it may concern:

Be it known that I, JAMES F. PIERCE, of Glynrich, in the county of New Castle and State of Delaware, have invented certain new and useful Improvements in Mandrels for Use with Apparatus for Forming Tubes, whereof the following is a specification, reference being had to the accompanying drawings.

10 The invention relates more particularly to a mandrel for use in a machine of the above character, wherein the tube is wound on the mandrel, completed thereon, and after it is finished, is withdrawn therefrom.

15 An object of the invention is to provide a mandrel of the above character, wherein the body portion thereof is formed in sections adapted to be collapsed to facilitate the withdrawing of the finished tube.

20 A further object of the invention is to provide a collapsible mandrel of the above character with devices wherein certain of the body sections may be first withdrawn toward the center of the mandrel before the 25 movement of the other sections so that the last named sections may be caused to overlap.

These and other objects will in part be obvious and will in part be hereinafter more 30 fully disclosed.

In the drawings, which show by way of illustration one embodiment of the invention, Figure I, is a longitudinal sectional view through a mandrel having my improvements embodied therein, said view being on the sectional line I, I, in Fig. III.

Fig. II, is an end view of the same, showing the mandrel collapsed.

Fig. III, is a cross sectional view on the 40 line III, III, of Fig. I.

Fig. IV, is a view similar to Fig. I, with the parts shifted for collapsing the mandrel.

Fig. V, is a view similar to Fig. III, with the parts shifted for collapsing the mandrel.

45 Fig. VI, is a sectional view on the line VI, VI, of Fig. III.

Fig. VII, is a detail sectional view along the line VII—VII of Fig. II, through the head and one of the supporting collars showing the adjusting screw for shifting the shaft relative to the head.

50 My mandrel is particularly adapted for forming tubes from a web of fibrous material, such as paper and the like. The web 55 is wound on the mandrel and is subsequently

subjected to a rolling and heating process, for finishing the tube, after which the tube is slipped from the mandrel. Said mandrel consists of a central shaft and supporting heads which are mounted on this shaft, and 60 also body sections which are supported by the heads and the shaft. These body sections are so supported that they may be moved toward the center of the mandrel and the mandrel thereby collapsed to facilitate 65 the withdrawing of the tube therefrom.

Referring more in detail to the drawings, my improved mandrel consists of a body portion which as herein shown, is formed in four sections 1, 2, 3, and 4. At the ends of 70 the mandrel there are supporting heads 5, and 6. Extending through the supporting heads 5, and 6, is a shaft 7. Supporting heads 5, and 6, are in the form of spiders, and each comprises four radial arms. Two 75 of these arms 8, 8, are shorter than the other two arms, which are indicated at 9, 9. The edges of the body sections 1, 2, 3, and 4, which meet directly over the arms 8, 8, are chamfered in opposite directions as at 10, 80 and 11. The other edges of the body sections which meet over the arms 9, 9, are squared. These body sections are also each provided with inwardly projecting arms 12, which are pivoted at 13, to arms 9, 9. 85

Fixed to the arms 9, 9, and extending from end to end of the cylinder are spacing and supporting webs 14, which remain in fixed position relative to the arms. By this arrangement the heads 5, and 6, when considered in conjunction with the fixed spacing webs 14, afford a rigid skeleton for the support of the movable part of the mandrel. Also extending from end to end of the cylinder are webs 15, these webs, however, having 90 sliding engagement with the arms 8, 8.

Mounted on the shaft 7, are two spaced collars 16, and 17. The collar 16, is connected by links 18, with the webs 15, while the collar 17, is connected by links 19, with 100 the webs 15. The collars 16, and 17, are secured to the shaft 7, by suitable set screws 20. Passing through the head 6, and also through the projection 21, on the collar 17, is an actuating screw 22. This screw is provided with a flange 23, and a square head 24, adapted to be manipulated by a suitable wrench. When screw 22, is turned, the collar 17, is moved toward or away from the head 6, depending upon the direction of 110

movement of the screw. Inasmuch as the collar 17, is fixed to the shaft 7, this movement of the collar causes the shaft to be shifted endwise, and with it the collar 16.

5 A link 25, is pivoted at one end to a lug 55, on the section 1, and at the other end to a lug 26, on the web 15. A similar link 25, is pivoted to the opposite web 15, and the section 4. A link 27, is pivoted to a 10 lug 57, on the section 2, and also to a lug 28, on the web 15. A similar link 29, is pivoted to the lug 59, on the body section 3, and to the web 15. It is to be noted that in the expanded state of the mandrel, as 15 shown in Fig. III, the links 27, and 29, are substantially perpendicular to the plane of the webs 15, while the links 25, are inclined to the plane of the webs 15. The result of this positioning of these links is as 20 follows:

As has been explained, the heads 5, and 6, are fixed and immovable, so that when the shaft 7, is moved, the webs 15, cannot move longitudinally with it, but the motion of 25 the collars 16, and 17, transmitted through the links 18, and 19, causes the webs 15, to move radially inward toward the shaft 7.

During this movement of the webs 15, the links 27, and 29, at first move the sections 2, and 3, to which they are attached very slightly, owing to the right angle disposition of the links relative to the plane of the webs, while the links 25, will immediately draw in the free ends of the body 35 sections 1, and 4, to which they are attached, and this inward movement of the sections 1, and 4, causes them to be moved beneath the free ends of the sections 2, and 3. A continued inward movement of all 40 the webs ultimately draws in the sections 2, and 3, and their free ends will overlap the free ends of the sections 1, and 4, as shown in Figs. II, and V, in which the mandrel is collapsed and the tube indicated 45 at T is released, so that it may be readily slipped from the mandrel.

The arrangement and proportioning of the links referred to affords in effect a delayed motion, so that one section may be 50 withdrawn before the other. It is obvious that this delayed motion may be accomplished in other ways than that herein shown. The essential feature of the invention consists in the means for collapsing the 55 mandrel by causing the body sections, which when in place form a full cylinder to overlap.

It is, therefore, obvious that minor 60 changes in the arrangement of the parts and the details of construction may be made without departing from the spirit of the invention, as set forth in the appended claims.

Having thus described my invention, I claim:

65 1. A mandrel for tube winding, includ-

ing supporting heads; a collapsible body comprising adjacent sections supported on said heads so as to swing toward one another and the center of the mandrel, in opposite directions with reference to said 70 heads, to collapse the body; and means for so swinging said heads, one in advance of the other so that they shall overlap, in collapsing said body.

2. A mandrel for tube-winding machines 75 including oppositely disposed stationary webs and oppositely disposed radially movable webs, a pair of sections pivoted to each stationary web on opposite sides thereof, and means connecting said pairs of sections to said movable webs on opposite sides thereof, whereby one section is moved inwardly prior to the adjacent section, so that said sections are caused to overlap.

3. A mandrel for tube-winding machines 85 including a plurality of pairs of sections forming a circular support, oppositely disposed pairs of stationary and radially movable webs, and means for pivotally connecting each section with a stationary and movable web, whereby one section of each pair is moved inwardly prior to the adjacent section, so that the sections are caused to overlap.

4. A mandrel for tube winding machines, 95 including supporting heads, a body composed of a plurality of sections, means for pivotally supporting said sections on said heads, movable webs adapted to move radially of said heads, and means whereby, 100 when said webs are moved toward the center of said mandrel, said sections are moved inward at adjacent edges, one prior to the other, so that said sections are caused to overlap.

5. A mandrel for tube winding machines, including supporting heads, a body composed of a plurality of sections carried thereby, arms supporting each section, said arms being pivoted on the supporting heads, and disposed on opposite sides of the center of the head, movable webs disposed adjacent the meeting edges of the body sections, means for moving said webs toward and from the center of the mandrel, links connecting said webs to the movable body sections, said links being so constructed and disposed as to cause one of the body sections to move toward the center of the mandrel prior to the adjacent body section, so 110 that the free ends of the body sections may be caused to overlap.

In testimony whereof, I have hereunto signed my name at Philadelphia, Pennsylvania, this nineteenth day of March, 1917. 125

JAMES F. PIERCE.
